WICKER, CANE, AND REED FURNITURE MANUFACTURE

Filed March 13, 1929

UNITED STATES PATENT OFFICE

JOHN FORST, OF NEW YORK, N. Y., ASSIGNOR TO MANHATTAN WICKER CO., OF NEW YORK, N. Y., A CORPORATION OF NEW YORK

WICKER, CANE, AND REED FURNITURE MANUFACTURE

Application filed March 13, 1929. Serial No. 346,657.

This invention relates to wicker, cane and reed furniture manufacture.

One object of the invention is to provide an improved furniture structure of the character described adapted to be used for chair, rocker and sofa seats or backs and for other purposes, and a novel method for making said structure.

Another object of the invention is to provide furniture structures of the character described comprising few and simple parts, which are easily assembled to form rugged and durable, yet attractive appearing structures, which shall be cheap to manufacture and practical and efficient to a high degree in use.

A further object of the invention is to provide an improved method of manufacture for furniture structures of the character described consisting in steps which shall be simple and easy to carry out and which shall require a relatively low degree of mechanical skill.

Other objects of this invention will in part be obvious and in part hereinafter pointed out.

This invention accordingly consists in the features of manufacture, steps in the process, combination of elements and arrangement of parts which will be exemplified in the manufacture hereinafter described and of which the scope of application will be indicated in the following claims.

In the accompanying drawing, in which is shown various possible illustrative embodiments of this invention,

Fig. 1 is a front elevational view of a cane chair seat or back structure embodying the invention.

Fig. 2 is a cross-sectional view corresponding to a cut taken on lines 2-2 in Fig. 1, and

Figs. 3 to 7, inclusive, are sectional views illustrating the progressive steps of the novel method embodying the invention.

Referring in detail to the drawing and more particularly to Figs. 1 and 2, 10 denotes an improved furniture structure adapted to be used for a seat or back rest

of a chair constructed to embody the invention.

The structure 10 is seen to comprise a ring frame 11 formed of any suitable material such as a bent wood annulus having a center opening O. Said frame may be of any desired shape such as square, rectangular, oval, etc., but is here shown as being circular.

Tightly stretched against one side of the frame 11 and extending over the opening O is a sheet 12 of woven cane, reeds or other material having resilient and wearing properties suitable to form a seat or back rest. The edge portion of the sheet 12 is looped to 12^a to conform with and tightly contact the periphery or perimetric region 11^a of the frame 11. Said sheet edge portion is extended beyond the peripherical region 11^a as at 12^b to contact against the wall 11^b of the frame opening, and is anchored to said wall by any suitable means such as nails 13 which pin the edge portion 12^b of the sheet 12 to the frame opening wall 11^b.

Finishing strips 14 of reed or cane are mounted and secured by nails 13, or other suitable fastening means, to cover the edge sheet portions 12^b for concealing the nails 13 and for serving as a finishing edge binding. Strips 14 also act as a secondary fastening anchorage for securing the sheet 12 to the frame 11 since said nailed strips 14 act to clamp the edge sheet portion 12^b to the frame opening wall 11^b.

Preferably an adhesive 15, such as a water-proof glue, is applied to the peripherical region 11^a before the sheet 12 is stretched thereover so as to provide an additional bonding or anchorage for better withstanding the strain of weight or pressure applied to the center 11^c of the sheet 11 over the opening O.

It should be noted that although the structure 10 is of very simple construction it is both light and rugged. The provision of the looped sheet portion 12^a with the main anchorage back of said portion at 12^b, forms an exceedingly strong construc-

tion which is capable of withstanding the roughest kind of wear and usage.

The upper rim edge surface of the structure 11 is left relatively smooth and even so as not to be uncomfortable to the user or interfere with his wearing apparel. The outermost binding strip 14^a extends below the peripheral region 11^a and may be positioned so as to be seen to serve as a trimming for the structure. When the structure is used as a seat without legs, the strips 14 serve as a base and protect the cane sheet against wear.

The novel method of making an improved structure 11 embodying the invention will now be described.

Referring now to Figs. 3 to 7, inclusive, F denotes a form having a stepped opening S, the latter being of the same contour as the frame 11 but slightly larger so that it can be loosely seated therein. A sheet of woven cane 11 after being soaked in water and while still moist is laid on the form F over the stepped opening S. The frame 11 is next pressed down into the stepped opening S carrying the sheet with it as shown in Fig. 4. While in this position the edge portion 12^a of the sheet is tightly folded around the frame and anchored by the nail 13 to the frame opening wall 11^b as shown in Fig. 6. The strips 14 are then applied over said nailed portion as shown, partially completed, in Fig. 7. If it is desired to add the adhesive bondage between at looped portion 12^a of the sheet and peripheral region 11^a, the latter is coated with a water-proofed glue or cement prior to inserting the frame 11 into the form F, as shown in Fig. 3.

After the cane sheet 11 has thoroughly dried, it will be drawn tight and leave the center of the sheet 11^c over the opening O sufficiently resilient to serve as a comfortable seat or back rest.

It will thus be seen that there is provided a manufacture in which the several objects of this invention are achieved and which is well adapted to meet the conditions of practical use.

As various possible embodiments might be made of the above invention, and as various changes might be made in the embodiment above set forth, it is to be understood that all matter herein set forth or shown in the accompanying drawing is to be interpreted as illustrative and not in a limiting sense.

Having thus described my invention, I claim as new and desire to secure by Letters Patent:

1. A method for manufacturing structures of the character described consisting in spreading a moist woven cane sheet over a stepped open form, inserting a ring frame into the stepped portion of the form to loop edge portions of the sheet about the periph-

ery of the frame, attaching said edge portion beyond the bight of the looped portion of the sheet, and applying a covering strip over said attached portion to the inner periphery of the frame.

2. A furniture structure comprising a ring frame having a center opening, a pre-formed unitary woven cane sheet mounted against one side of the frame over said opening and having portions bent around the outer periphery and secured to the inner periphery of said ring and a covering strip secured over said sheet to said inner periphery of the ring.

3. A furniture structure comprising a ring frame having a center opening, a pre-formed unitary woven cane sheet mounted against one side of the frame over said opening and having portions bent around the outer periphery and extending to the inner periphery of said ring and fastening means securing said bent around portions to said inner periphery of the ring and a covering strip over said fastening means.

In testimony whereof I affix my signature.

JOHN FORST.
